UNITED STATES PATENT OFFICE.

CHARLES STEINFELS, OF ELIZABETH, NEW JERSEY, ASSIGNOR TO HIMSELF AND WILLIAM HARRIS, OF SAME PLACE.

SCREW-POLISHING MACHINE.

SPECIFICATION forming part of Letters Patent No. 236,103, dated December 28, 1880.
Application filed November 1, 1880. (No model.)

To all whom it may concern:

Be it known that I, CHARLES STEINFELS, of Elizabeth, in the county of Union and State of New Jersey, have invented a new and useful Improvement in Machines for Polishing Screws, of which the following is a specification.

My improvements relate to machines for polishing the heads of screws, and have for their object to construct an automatic machine which shall take the screws as fed in mass and present them properly to the polishing-wheels.

The invention consists in a feed-belt which first receives and sorts the screws and delivers them, singly and uniformly, in a feed-wheel provided with nippers that take the screws from the belt and deliver them, point first, to the nippers of a wheel or drum that presents the heads to the grinding and polishing wheels; in nippers of novel construction and mechanism for operating them properly, and in certain other novel details of construction, all of which will be particularly described hereinafter, with reference to the accompanying drawings.

In the drawings, Figure 1 is a side elevation of the machine with the feed-box broken open. Fig. 2 is an end view, in section, on line $x-x$ of Fig. 1. Fig. 3 is a section on the plane of the axis, and Fig. 4 a section at right angles to the axis, of the holding-wheel; and Figs. 5, 6, 7, and 8 are detail views, referred to hereinafter.

Similar letters of reference indicate corresponding parts.

a are the standards of a frame of suitable height, on which standards drums or pulleys A are mounted. Around these drums is a flexible belt, b , which is fitted with numerous clutches, b' , that are arranged in diagonal lines across the belt, as illustrated in Fig. 8.

On the frame above the pulleys A a plate, c , is fixed a short distance above the upper side of the belt. This plate, which I call the "distributing-plate," is slotted lengthwise, or consists of a number of strips placed a distance apart slightly more than the diameter of the screws.

Above one end of the plate is fixed the dis-

tributing-box B , and above box B is the feed-hopper C , having an opening in its bottom, in which is fitted a revolving roller, d , having flanges or pins, as shown, which regulate the discharge of the screws into box B . The box B is fitted with inclined plates or shelves e , which are corrugated and terminate one above the other, so that the screws roll down by gravity from one to the other shelf, and finally drop upon the plate c , the corrugations serving to make the discharge successive.

The clutches b' of the belt b are constructed as shown most clearly in Figs. 6 and 7. f is a post riveted to the belt and stiffened by a brace, f' . g are fingers pivoted on the upper end of post f to open and close in a horizontal plane, and having their forward ends shaped to fit the screws.

On the brace f' is hung a bent lever, g' , the lower end of which extends through a slot in the belt, while the upper end is fitted with a wedge, g^2 , extending between the rear ends of fingers g , so that the fingers are opened and closed by movement of lever g' . The lever g' is fitted with a spring, f^2 , that tends to retain fingers g open. The wedge g^2 is formed of two hinged pieces kept apart by springs, which allow for variations in size of screws.

Beneath one end of belt b are tubes or spouts h , the upper ends of which are made flaring, and the lower ends run together and terminate in a single spout, h' . As shown in Fig. 2, the tubes are fitted where they connect with hinged flaps h^2 , which, being moved by the screws passing through, prevent more than one screw passing at a time into the tube h' , and thus prevent clogging, and also insure the screws passing endwise. At the end of tube h' is a hinged flap, h^2 .

In suitable bearings beneath tube h' is fitted a receiving wheel or drum, D , as shown in Fig. 2, which wheel is shown in edge view in Fig. 5, and is constructed as follows: The wheel is formed of two disks, i , of spring metal, secured on a shaft a short distance apart. To these disks, between the outer edges, V-shaped pieces i' are secured at regular intervals, which pieces are so formed as to grasp and hold the heads of the screws when the sides of the drum are pressed together. Between the gripping-

pieces i' the disks i are formed with inward flanges i^2 , which act to support the screws before they drop into the grippers.

At the sides of wheel D, and forward of tube 5 h' , there are fixed on the frame of the machine curved plates or segments k , which incline inward from the tube h' , so as to press the sides of the wheel together as they pass between the segments, the sides springing outward 10 again after clearing the segments.

At the forward side of wheel D is placed 15 the polishing machinery, consisting of a holding-wheel, E, polishing-wheels $l l l$, hung in a frame, l' , in position for polishing the faces of the screw-heads as they are carried around by wheel E, and polishing-disk l^2 , for the sides of the heads. The wheel E is loose upon a fixed sleeve or hub, m , through which the shaft m' passes loosely, such shaft having a continuous 20 rotation given through medium of a worm-wheel, m^2 . (Shown in Fig. 1.) The wheel D is hollow, as shown in Figs. 3 and 4, and has one side formed by a disk, E' , on the center of which is a bevel-gear, n' , meshing with a similar gear on a shaft, n , that connects by bevel-gearing with the shaft of wheel D, so that 25 wheels D E shall move together but in opposite directions. On the same side of wheel E are ratchet-teeth o' , that are engaged by a lever-pawl, o , which is vibrated by an eccentric, o^2 , fitted on a revolving shaft and given a continuous rotation by suitable connections, so that the lever-pawl o acts to give wheel E, and consequently wheel D, an intermittent rotation. 30 The wheel E is fitted at regular intervals with radial pins p , which project into the chamber and are sustained by a flange, p' , while their outer ends are fitted with hinged fingers q , formed to receive the shanks of the screws between them. The wheel is formed with inclined lugs q' at opposite sides of fingers q , and the fingers correspondingly shaped, so that 35 inward movement of pins p shall close the fingers together, suitable springs being provided to spread the fingers open when released by outward movement of the pins. The pins p are fitted with spiral springs q^2 , which tend to move them inward, and thus close the fingers. 40

On the inner ends of the pins are loose bevel-gears r , meshing with a wheel, r' , that is fixed 45 on shaft m' . The gears r are fitted with radially-moving latch-pins s , moved inward by springs and engaging with notches in pins p when the latter are at their inward position, 50 so that the pins are connected with the gears.

On hub m is a cam-segment, t , over and in contact with which the pins p move during half or more of the revolution of wheel E, so that they are forced outward. By this construction the pins and nippers are given a rotary motion while being carried around with the wheel, and also have movement in and out. 55

The operation of the machine is as follows: The screws are placed in mass in hopper C, 60 are fed one by one, by roller d , to the inclined shelves e , and pass down upon the slotted plate c . Those that fall in line with the slots re-

main suspended by their heads, and these, when moved forward by the belt, move the others into line with the slots, so that all are 70 finally suspended. The belt b moving beneath the plate with its clutches b' in line with the slots, the post f carries the screws forward in the slots until the belt reaches the pulley A, when, by contact with the pulley, the levers 75 g' are raised, the fingers g close on the screws, and they are carried out of the slots and around the pulley A to the tubes h' , which, being placed to receive the screws at the moment they are relieved by the belt leaving the 80 pulley, the screws enter the respective tubes, head first, and pass in succession to the tube h' . The lower screw in the tubes rests on the flanges i^2 of wheel D until, by rotation of the wheel, the grippers i' receive the head, the segments k close the grippers, and the screw is carried out, the flap h^2 giving way for it to pass. The screw is thus carried toward wheel E and presented, point first, to the grippers g , which close upon it the moment or before 90 85 grippers i leave the segments k . The screws are thus presented successively to wheel E, and are taken up by the latter, which carries them into contact with the revolving polishing-wheels $l l'$. After passing the upper wheel, 95 l , the pins p pass upon the cam t , and are thereby forced outward, so that the screws drop. The successive operations are thus automatically performed, and with rapidity.

I have shown five grooves in plate c and 100 five tubes; but the number may be increased, the wheels D E being made proportionately large in order to give space for the increased number of grippers required. The grippers may also be arranged in two or more lines, if desired, and the tubes h h' arranged in sets to correspond. For round-headed screws the polishing-wheels l' will be grooved.

Having thus fully described my invention, I claim as new and desire to secure by Letters 110 Patent—

1. In screw-polishing machines, the combination of feed-box B, slotted bed c , moving endless belt b , provided with clutches b' and carried by pulleys A, receiving tubes h h' , revolving wheel D, provided with grippers i' , holding-wheel E, provided with clutches g , and polishing-wheels l l' , substantially as shown and described, and arranged for the successive operations, as specified. 115

2. In screw-polishing machines, the combination of wheel D, provided with grippers fitted to take up and release the screws, wheel E, provided with clutching-fingers fitted for automatically receiving and releasing the screws, 120 polishing wheels or disks, placed to act on the screws, and mechanism for giving simultaneous intermittent motion to the wheels D E, substantially as shown and described.

3. In screw-polishing machines, the automatic sorting and feed mechanism consisting of box B, provided with inclined shelves e , slotted bed or plate c , traveling endless belt b , provided with clutches b' , tubes h h' , and

receiving-wheel D, provided with gripers i' , combined for operation substantially as shown and described.

4. In screw-polishing machines, the receiving-wheel D, consisting of spring-disks i , provided with gripers i' , flanges i^2 , and pressing-segments k , combined with feed-tube h' , and wheel E, fitted to take the screws, all substantially as shown and described.

5. In screw-polishing machines, the combination, in the revolving holding-wheel E, of notched sliding pins p , fingers q , lugs q' , spring q^2 , pinions r , latches s , gear-wheel r' , revolv-

ing shaft m' , fixed sleeve m , and cam t , substantially as shown and described, for operation as specified. 15

6. In screw-polishing machines, the nippers b' , consisting of post f , gripers g , lever g' , wedge g^2 , and spring j^2 , combined with the slotted feed-belt b and pulley A, substantially as shown and described, for operation as specified. 20
